(57) **CLAIM**

The ornamental design for a motor vehicle and/or toy replica thereof, as shown and described.

DESCRIPTION

FIG. 1 is a left, front perspective view for a motor vehicle and/or toy replica thereof showing our new design;

FIG. 2 is a left, rear perspective view thereof;

FIG. 3 is a right, front perspective view thereof;

FIG. 4 is a right, rear perspective view thereof;

FIG. 5 is a front view thereof;

FIG. 6 is a rear view thereof;

FIG. 7 is a left side view thereof;

FIG. 8 is a right side view thereof; and,

FIG. 9 is a top view thereof.

The bottom view of the motor vehicle and/or toy replica forms no part of the claimed design.

It is certified that error appears in the above-identified patent and that said Letters Patent is hereby corrected as shown below:

On the Title Page

Item (71) should read as follows:

(71) Applicants: **Kazuhiro Sato**, Nisshin-shi (JP); **Junwon Han**, Okazaki-shi (JP)

Item (72) should read as follows:

(72) Inventors: **Kazuhiro Sato**, Nisshin-shi (JP); **Junwon Han**, Okazaki-shi (JP)

Item (73) should read as follows:

(73) Assignee: **Toyota Jidosha Kabushiki Kaisha**,
Toyota-shi, Aichi-ken (JP)

Signed and Sealed this
Fourth Day of February, 2025

Coke Morgan Stewart
Acting Director of the United States Patent and Trademark Office
